VIBRATOR

Georges Walter, Perroy, Switzerland

Application December 21, 1945, Serial No. 636,407
In Switzerland December 21, 1944

10 Claims. (Cl. 259—1)

1

The present invention relates to improvements in vibrators of the type wherein two elements are caused to rotate one in relation to the other, the stationary element providing a rolling way or a shaft for the rotating element, one of these elements being circular and the other non-circular, the latter comprising however a continuous curve without any angles between adjacent zones of different radii of curvature.

Numerous mechanisms have been proposed for the production of vibrations more or less complex and particularly by using rotative elements generating vibrations of pure sinusoidal character.

Some of these apparatuses are composed simply of an excentric mass in rotation around a shaft and which under the effect of centrifugal force, produces such vibrations of frequency equal to the number of revolutions performed in the unit of time.

Others set rolling a mass comprising an element of circular profile, interiorly or exteriorly to a rolling way of same profile, producing also vibrations according to the sine law, but of frequency differing generally from the number of revolutions in the unit of time imparted to the rotative element. Such apparatuses enable, in particular, to obtain relatively high frequencies with a motor of comparatively low speed. The axis of the mass describes either a cylinder or a cone, according to the mode of suspension, the mode of driving and the rolling ways used.

Finally it has already been proposed to assemble in a single apparatus an excentric mass and a mass leaning on a rolling way and, which, while allowing the use of single driving means of uniform speed, produces the superposition of sinusoidal vibrations of different frequencies and the obtaining of the varied interference effects resulting therefrom.

None of these apparatus allow however the production of vibrations showing, even temporarily, characteristics of steep front waves, i.e. which produce shocks repeating themselves more or less often and rapidly.

Constructions are already known, showing a mass effecting a to-and-fro movement, with or without springs, but in less rational conditions, owing to the discontinuity of the type of motion adopted. The internal shocks due to the inversions of direction overstrain the corresponding organs beyond their limit of elasticity, overheating them uselessly and gradually destroying them.

A mass subjected to a to-and-fro motion is not suitable for the realisation of very high frequencies.

2

But according to the present invention unlike the known devices of this kind, one of the two elements that the effect of centrifugal force applies one against the other in order to obtain the rolling phenomenon, is not circular.

Among the various radii of curvature composing this non-circular element, it is evident that at least one radius differs less than the other ones from the radius of the circular rolling way. It will be seen that the zone having this particular radius will develop higher forces than any other zone and that the said force will increase in inverse ratio to the difference of the considered radii. When the difference is zero, the force developed can be theoretically infinite, but only in practically no interval of time.

So to say, in a preferred embodiment of the object of the invention, the non-circular element presents at least one zone where the radius of curvature is comprised between the constant radius of the other circular element and another radius of curvature differing from it in a slight proportion, the said non-circular profile comprising no angular passage and being constituted, with the exception of the case of equality between the particular zone above mentioned and the constant radius of curvature, either solely by portions of larger, or solely by portions of smaller radii than the latter.

The first case, comprising solely equal or larger radii of curvature, is applied to those apparatuses in which the circular element is placed in the interior of the non-circular element, the second case, comprising only equal or smaller radii of curvature, is applied to the inverted disposition, i.e. where the circular element envelops the non-circular element.

It will be seen further that the proposed solution has a very high acuteness in regulating the characteristics of the vibratory shocks obtained, which fact in particular allows of the adaptation of the power of these latter to the maximum efforts which the organs concerned can transmit and support without prejudice or local modifications.

The enclosed drawing explains by graphs and diagrams how a vibration apparatus works according to the invention and represents an illustrative embodiment given by way of example.

Fig. 1a is a graph showing the interior and exterior profiles of two organs destined to roll one upon the other according to the rules imposed by the present invention.

Fig. 1b is a diagram of the vibrations obtained by the application of constructive elements making use of the already mentioned profiles.

Fig. 2a is a graph similar to that of Fig. 1a from which it differs by the form of one of the elements in presence.

Fig. 2b is the diagram of the vibrations obtained by the application of constructive elements making use of the modified profiles already mentioned.

Fig. 3 reunites the graph and the diagram of a disposition differing again from the two already mentioned.

Fig. 4 shows an example of two profiles, practically utilizable for the establishment of the rolling ways of a determined vibrator.

Fig. 5 is a longitudinal axial cross-sectional view of an example of a vibrator, constructed according to the invention, while

Fig. 6 shows a partly transversal cross section and

Fig. 7 shows a detail of the same illustrative example.

A pivot 2 is placed in this cavity and serves in its turn, as rolling way for the said mass, presumed to be rotatively moved in the direction of arrow 3. As a result of the foreseen play between these two elements, the mass will be submitted to an eccentric rotative motion which tends constantly to apply it against all the points, or more exactly against all the generating lines of the pivot.

The latter has a particular profile, composed of four distinct zones, which may be indicated by A—B, B—C, C—D and D—A the characteristics of which are as follows:

The zone A—B has the same radius of curvature as the circular cavity 1.

The zone B—C has a notably smaller radius.

The zone C—D has a radius of curvature lying between the two above mentioned.

The zone D—A has the same radius of curvature and the same arc as the zone B—C.

The tangents at the points A, respectively B, C, and D are also each of them and simultaneously lined up to the two contiguous zones ending at each of these points, so that the pivot does not present any angle.

The result of this is that if the mass presenting the cavity 1 is set in motion around the pivot 2, it will travel from the position, shown, successively and without stop to arcs B—C, C—D, D—A and A—B and so on.

According to a well known law, the effort of centripetal application exerted against the pivot while rolling from B to C is a constant, the determined value of which is function of the mass, of its rotation speed and of the ratio of the considered radii the gravity action being abstracted.

The proceeding will be the same but with a modified value due to the variation of the radius ratio, during the rolling time from C to D, whereas between D and A the same conditions as between B and C will again be reproduced, for reason of symmetry.

Whereas, owing to the evenness of the radius of curvature of the cavity and of the zone A—B, the mass, when it arrives in A, which point will act momentarily as rotation centre, will suddenly crash against the pivot, falling exactly upon it and thus producing in practically no interval of time a shock developing a theoretically infinite force.

During the time of travelling the axis of cavity 1 describes the curve 4, the singular point of which, constituted by point 5 corresponds to the instantaneous passage from A to B.

By the intermediary of pivot 2, the above mentioned centripetal forces can be transmitted to the frame not represented of an apparatus provided with means destined to transmit in its turn a resultant directed to an object, a mass, etc., which is to be subjected to a vibratory effect.

The variation in time of the effort thus transmitted in the direction of arrow 6 can be seen on the diagram of Fig. 1b, the abscissae of which give the time whereas the ordinates give the measures of said force.

Reading the curve of this diagram, from left to right on the drawing, the point 7 in AB gives the momentarily infinite value developed at the time of the instantaneous shock produced by the conjuncture of the interior of cavity 1 with the zone A—B of pivot 2.

Immediately after this maximum, the transmitted effort assumes again a finite value, which varies according to the sine law at the time of the passage from B to C, along the portion 8 of the traced curve.

From C to D the effort follows likewise the said law, in conformity with the portion 9 of the curve, which is displaced owing to a sudden increase of the effort in C and a corresponding decrease in D, which are due to the passage from one radius of curvature to the other. This increase, resp. decrease involves the presence of the two connecting lines 10 and 11, marked by dotted line, perpendicularly to the axis of the abscissae.

In a similar way, point 1 is represented by dotted line of same orientation, for the described shock finally carries on to infinity a sinusoid resolving itself into a point.

From D to B, the variation is symmetrical from 8 to 12 and finally reaches again a maximum value infinitely large in 13, after which the described cycle recommences.

This diagram differs only from the reality by the impossibility of showing in the drawing the points 7 and 13 to infinity and of representing side by side two separate lines representing a quantity of time null. The spaces admitted on the drawing are therefore relatively too large with respect to the other part of the curve, which is exact.

In order to allow a comparison with what is effected in the known devices with circular rolling, the curve 14 in dotted line, shows what would be, all conditions being equal, the efforts of sinusoidal variations transmitted by a circular pivot having a radius corresponding approximately to the arithmetical means of arcs A—B, B—C, C—D and D—A.

Fig. 2a concerns a case approaching that which has just been described. The difference is that the four zones E—F, F—G, G—H and H—E of pivot 15, have all a radius of curvature differing from the constant radius of cavity 16 and smaller than this latter.

The zone E—F presents a radius just slightly inferior to that of the cavity, whereas the zone F—G has a notably smaller radius, the zone G—H an intermediary radius and the zone H—E the same characteristics as the zone F—G.

The direction of rotation is admitted, as in the above mentioned example, to correspond with that of arrow 17, the mass presenting the cavity turning in that direction around the pivot 15.

The line 18 shows the course taken by the centre of this cavity, respectively by its axis in front view.

In the position shown this curve is more

5

rounded at its upper part and more tapered without being pointed at its lower end.

Owing to the slight difference between the radius of curvature of the zone E—F and the interior of cavity 16, the example given suppresses the sudden shock of time practically null, which effect would exceed the effort the material of the apparatus frame is able to transmit without to transform a part of the energy in heat, and replaces it by a very violent shock of very short duration, the shorter in proportion as the considered radii have more resemblance.

The curve of the diagram represented in Fig. 2b shows the working process, the transmitted efforts being always considered in the direction of arrow 19.

At the moment of the passage by zone E—F and during a space of time which is now represented in the diagram at the exact scale, a very high maximum value 20 is produced, of sinusoid form and displaced as above explained, at the extremity of the ordinates, right lines parallel or perpendicular to the abscissae axis, which the diagram shows in dotted lines.

Following this equally violent shock, one finds again on the three other zones of the pivot effects corresponding to what has been already explained with regard to Fig. 1a and 1b.

At each passage from E—F however a maximum value as for example 21 is reproduced and this will be the case once for each cycle.

It is easy to understand that, by a precise adjustment of the pre-determined difference between the interior radius of curvature of cavity 16 and the exterior radius of the zone E—F of the pivot, the radius of which is quite near, it is possible to give the points 20, 21, etc., a certain value which can be controlled and consequently to fix a limit of the forces which the whole apparatus can transmit without risk of local deterioration and with a minimum of loss of energy, the vibrations thus obtained being obviously much more powerful than those which any similar apparatus with purely sinusoidal characteristics could produce.

Fig. 3 shows the working in this case, for example in the case of a cavity 22 in which would turn a pivot 23, moving in the direction of arrow 24 and having a zone I—J with radius of curvature very near or equal to that of the cavity.

In the represented position of the pivot, there will be produced a shock or radial maximum action set in the space in conformity with the curve 25. But owing to the difference of the perimeters between the pivot and the cavity, it is clear that this shock will not be regularly reproduced in 25, but after having provoked more or less similar shocks in intermediary directions, the pivot will provoke one shock in 26, and afterwards in 27, in 28, etc., so that instead of having directed vibrations, there will be on the contrary vibrations or shocks radially distributed in all directions around the cavity.

Therefore, according to whether one turns what constitutes the interior rolling way or the pivot, or, on the contrary, the exterior rolling way or cavity of the cooperating elements there will be obtained, at will, directed vibrations or vibrations radiating in all directions, this however always with the possibility of regulating the power in a precise way according to the material and the type of construction used.

Whereas in the above description it has been admitted that a non-circular pivot cooperates with a circular cavity, it is obvious that it is also

6

possible to make a circular pivot cooperate with a non-circular cavity.

In this case the various radii of curvature of the cavity profile will all be larger or at least equal to those of the pivot, the directed vibrations being now obtained by rotative motion of the pivot in the cavity serving as bearing, whereas the radially dispersed shocks will correspond to the inverse working.

The examples represented so far were purely schematic but reflected in a precise manner the practical working, showing also what possibilities the present invention may lead.

Fig. 4 gives a concrete example, i. e. indicates measures which can be used for a well determined construction of a vibrator which corresponds to the conditions of the present invention.

A pivot 29 with uniform radius of curvature of 60 mm. being admitted, the cavity 30 with 20 which it cooperates presents successively at 64 mm. radius from K to L, on an arc of 194° 54', a 72.7 mm. radius from L to M, on an arc of 37° 33', a 60.5 mm. radius from M to N, on an arc of 90° and finally a 72.7 mm. radius from N to K, on an arc of 37° 33'.

The zone the radius of which is very close to that of the pivot, is therefore the zone M—N with 60.5 mm. radius the difference being only 0.5 mm.

It is interesting to see how the centres of the various radii of curvature are placed the one with regard to the other in order to obtain a continuous curve, free from any angular passage.

Admitting the centre 31 for the radius of arc K—L and the centre 32 for arc L—M, these two centres are in alignment with the point of junction L. The centre 33 of arc M—N, following the centre 32 of arc L—M, is in its turn, in alignment with 32 and M and the centre 34 of arc N—K in alignment with the points 33 and N, 40 whilst finally 34, 31 and K are also on a common line.

If we admit a direction of rotation of the pivot 29 corresponding to arrow 35, said pivot is represented at the moment when the mass which it constitutes, or which is joined to it, leans against the point N and is about to roll from N to M which owing to the similitude of the radii, takes a very short time, i. e. the time the pivot takes to pass from position 29 to position 29'.

It is at this moment that the apparatus provided with the elements represented and the cavity 30 of which will be joined to its frame, will develop a particularly high degree of energy in the direction of arrow 36 and will therefore be able to transmit this energy to whatever tool or organ one desires, putting thus in vibration a material or a given object according to the characteristics given by the diagram of Fig. 2b. The vibrator according to Fig. 5 to 7 is of a type, the mass of which is driven from the exterior, by means of a flexible shaft and the frame of which would comprise for example a non-circular cavity having the dimensions given on Fig. 4, in which a cylindrical mass-pivot would turn as shown in 29 of this figure.

This mass is here constituted by a metallic sleeve in two pieces 37, 38, surrounded by a rim 39 in particularly hard and well ground material.

This rim presents a circular flange 40 which will roll along the path 41 of the apparatus frame, this rolling way presenting consequently the same profile as the piece 30 of Fig. 4.

The rotative driving of the mass starts from a flexible member ending in 42, under a hand wheel 43 allowing the operator to grasp the vibra-

tor, and is transmitted by means of bevel gears 44, 45, the spherically faced square 46 cooperating with the square-holed barrel 47, the shaft 48, the bevel gears 49, 50 and the shaft 51, which drives the mass by means of a kind of cardan composed of a cross-bar 52, a two pieced ring 53 (see also Fig. 6) and of the two fingers 54 and 55 emerging from said mass and penetrating into the said ring.

The hand wheel is further joined to the apparatus frame by the intermediary of a piston 56, the central shoulder 57 of which is held between the two compression springs 58 and 59 borne by the cylindrical projection 60 of the above mentioned frame.

The object of this disposition is to deaden the shocks transmitted to the hands of the worker, a deadening which can in a certain degree be regulated by a threaded ring 61 acting on compression springs 58, 59.

A sliding key 62 prevents the rotation of the hand wheel with respect to the frame, this being indeed necessary not only for the good working of the apparatus, but also because the bearings 63 of gears 44 and 45 are placed on this hand wheel.

In consequence of the elasticity conferred to this mechanism, the motive power must be transmitted by the intermediary of square 46 and of barrel 47 allowing a certain axial play.

This is an advantage not only in favor of the worker, but also for the flexible shaft ending in 42, always a more or less delicate organ, and which will therefore not be directly submitted to the shocks emitted by the vibrator.

At the side opposite to flywheel 43, the frame of the apparatus presents a projection 64, to which tools may be fixed by any known method, in order to transmit the vibrating action to the materials or objects to be vibrated.

It is obvious that a vibrator of the above description is an apparatus of precision and will only work satisfactorily on condition that it is kept carefully free from any deterioration.

The rolling ways 40 and 41 in particular must always be perfectly smooth and must keep, the one, its strictly cylindrical form and the other, the profile assigned to it.

Any shock which would have for effect to injure these rolling ways would consequently be hurtful. Or, as such shocks might be produced for example after skidding when starting, when the mass is still not sufficiently set in motion, the apparatus can comprise a special device ensuring a rapid starting, without direct effect on the above mentioned rolling ways.

For this purpose, the rim 39 of the interior cylindrical mass presents a flange, which comprises on each side an inclined plane 65, resp. 66, whereas the frame presents on each side of the rolling way 41, similar inclined planes, one of them belonging to a fixed ring 67 and the other to a ring 68 axially movable against the action of an elastic washer 69.

The axial displacement of this ring 68 is produced by the rotative motion, by means of lever 70, of a ring 71, which is shown in detail on Fig. 7. This ring comprises wolf-teeth such as 72, the inclined planes of which cooperate with corresponding inclined planes of the ring 68, allowing the transformation of the rotative motion into an axial thrust against the ring 68 in the direction of the apparatus center (position of Fig. 5), against the action of the elastic washer 73.

69, or on the contrary to let it fall back under the action of said ring.

In the advanced position represented on Fig. 5, the cylindrical rotative mass does not in fact strike the rolling way 41, but leans by the inclined planes 65 and 66 against the corresponding inclined planes 67 and 68. That is the starting position.

In this position there is moreover a slight jamming between the faced surfaces, which fact ensures the necessary adhesion for a rapid starting.

As soon as the normal working speed is reached, the operator lets the ring 71 fall back by moving the lever 70.

15 At this moment the contact between the rolling ways 40 and 41 is established and the apparatus can instantaneously produce the vibrations corresponding to its characteristics, vibrations of the kind represented on the diagram of Fig. 2a.

20 By making the rolling ways and the rotative mass longer or by connecting several vibrators together, it is possible to transmit synchronous vibrations of until now not realised power and frequency to very large objects.

25 Instead of driving exteriorly the rotative mass, it would also be possible to give it a motive power, i. e. to constitute the rotative mass by means of a part of a motor and particularly of an electric motor.

30 It is obvious that any rotative motor, the mass of which can support the vibrations or shocks resulting from the claimed disposition can be applied to the execution of the invention.

35 The embodiment according to Figs. 5 and 6 comprises special means ensuring the driving of the mass due to the ring 71.

It is obvious that other means could be foreseen, for the same result, i. e. preventing the skidding of the rotative mass when it works.

40 It is easy to understand how the mass, by turning, will be obliged to follow the trajectory which is imposed to it by the profile of the faced rolling ways.

45 Whereas the embodiment according to Figs. 5 to 7, whereas the direction of the shocks is imposed by the construction, it is possible to distribute the said shocks in all directions, radially around the axle of the apparatus.

However there is another solution, which allows, for example, to modify by construction the direction imposed on the shocks.

50 It would simply suffice, for example, to foresee that the rolling way 41 of the apparatus of Fig. 5, can turn around the axis 51 and be immovably fixed in the desired angular position. This would give the possibility of orienting it at will in the zone space, the radius of curvature of which would give the maximum thrust.

55 The different suggestions of carrying out the invention in combination with an electric motor are mentioned only by way of example and it is obvious that it can always be carried out in combination with any source of rotary power without in any way limiting the scope or spirit of the invention.

60 What I claim is:

65 1. A vibrator comprising a first element having a noncircular recessed inner surface, a second element having a circular projecting surface inserted in the recess of said first element, said recessed surface having circular zones of radius at least almost equal to the radius of said projecting surface, means for rotating said first element around said second element with said surfaces in mutual contact substantially through-

out the axial direction thereof, and a frame rigidly attached to said second element.

2. A vibrator comprising a first element having a circular recessed inner surface, a second element having a noncircular projecting surface inserted in the recess of said first element, said projecting surface having circular zones of radius at most almost equal to the radius of said recessed surface, means for rotating said first element around said second element with said surfaces in mutual contact substantially throughout the axial direction thereof, and a frame rigidly attached to said second element.

3. A vibrator comprising a rolling way element and a rotary mass element adapted to roll on said rolling way means for applying said mass against said rolling way by centrifugal force throughout substantially the whole length of said rolling way, one of said elements being circular and the other noncircular, said noncircular element having a first zone with a radius of curvature almost equal to the radius of said circular element, a second zone with a radius slightly different from the radius of said first zone, and at least one zone with a radius intermediate the radii of said first and second zones.

4. A vibrator comprising a rolling way element and a rotary mass element adapted to roll on said rolling way, means for applying said mass against said rolling way by centrifugal force throughout substantially the whole axial length of said rolling way, one of said elements being circular and the other noncircular, said noncircular element having a first zone with a radius of curvature only slightly different from the radius of said circular element, a second zone with a radius slightly different from the radius of said first zone, and at least one zone with a radius intermediate the radii of said first and second zones.

5. A vibrator as claimed in claim 4 wherein the radii of said zones are all larger than the radius of said circular element.

6. A vibrator as claimed in claim 4 wherein the radii of said zones are all smaller than the radius of said circular element.

7. A vibrator as claimed in claim 3 wherein said noncircular element is entirely composed of curved zones without intermediate angles.

8. A vibrator as claimed in claim 4 wherein said noncircular element is entirely composed of curved zones without intermediate angles.

9. A vibrator comprising a frame having an inner, noncircular rolling way, a cylindrical mass adapted to roll on said rolling way and to be in rolling contact therewith throughout substantially the whole axial length thereof, said way being a continuous curve having zones of curvature with radii partly larger than and at least partly almost equal to the radius of said cylindrical mass, a vibration transmitting organ oriented according to a radius traversing the zone of said rolling way having the radius nearest to the radius of said cylindrical mass, and means for attaching said organ to said frame.

10. A vibrator as claimed in claim 9 wherein said continuous curve presents no angles between adjacent zones.

GEORGES WALTER.
